UNITED STATES PATENT OFFICE

BENJAMIN OSTROFF, OF GARDNER, MASSACHUSETTS

CUSHION

Application filed October 22, 1931. Serial No. 570,302.

This invention relates to cushions, being intended more particularly, though not exclusively, to provide an improved form of pillow cushion of the type commonly employed in connection with upholstered chairs, sofas, davenport and other structures intended to support the occupant in a sitting or reclining posture, the term pillow cushion being intended generically to include such various applications thereof.

Such cushions are commonly made up in the form of padded, resilient units and more or less flexible, but having a characteristic shape designed to be preserved, and suitably shaped for application to the seat of a chair or sofa which is itself frequently provided with a built-in under-spring construction, the cushion being designed to provide an added softened cushioning effect for the chair or sofa as well as to produce a finished and heavily upholstered appearance. To fulfil these conditions, it is desirable that the cushion unit should be detachable, capable of preserving its intended shape and being restored to its full expanded form when relieved of pressure, and also capable of being reversed so as to provide its resilient cushioning effect in either of its reversed positions.

Pillow cushions of this type have heretofore proven most comfortable when stuffed with down, but a down filling tends to pack more or less through continued usage, causing the unit as a whole to lose its plump, expanded form and the outer covering to become creased and marred. Pillow cushions provided with resilient springs alone to give the cushioning effect tend to give either a harsher cushioning effect than is desired on the one hand or an entirely too yielding response on the other hand.

One object of the present invention is to provide a resilient pillow cushioning unit in which the cushioning effect of springs is utilized but supplemented by the effect of a yielding air cushion, the unit being detachable and reversible and presenting a cushioning seat in either reversed position, the unit being so constructed that the air cushion will function equally well in either position and a cushioning effect produced approximating

closely that of a down-stuffed cushion, while the cushion, even under long continued usage, continues to retain its plump, expanded and originally designed shape and form.

The invention will be best understood by reference to the following description when taken in connection with the accompanying illustration of one specific embodiment, while its scope will be more particularly pointed out in the appended claims.

In the drawing:

Fig. 1 is a perspective showing a pillow cushion embodying one form of the invention, the outer elements of the cushion being partly detached and turned back to show the interior construction;

Fig. 2 is a cross-section, in elevation, taken through the cushion and showing the internal resilient unit with its flexible air-tight covering;

Fig. 3 is an enlarged detail in section showing the flexible air pipe connecting the air space of the internal resilient unit with the outer casing; and

Fig. 4 is a side elevation of the valve employed for regulating the admission and the escape of air.

Referring to the drawing and to the illustrative embodiment of the invention shown, the cushion as disclosed in Figs. 1 and 2 is provided with an internal resilient unit having a series of helical springs 11 arranged side by side in rows and held separated in place by any desired means. This internal resilient unit, which is of generally rectangular shape in plan, thus has, as a whole, a definite and characteristic but yieldable and more or less flexible form throughout. It is covered on the top, bottom and sides by a flexible but air-tight covering 13 of any suitable material, such as rubberized cloth, the same forming, except for the vent opening hereinafter referred to, a substantially air-tight chamber in which the springs are contained.

The springs 11 may be fastened together either directly to the covering 13 or by any other desired means, but herein they are secured to upper and lower sheets 15 of coarsely meshed fabric, such as burlap, which to-

gether with longitudinal and transverse strips 17 of the same material are formed into a kind of a cellular casing in which the springs are secured and which holds the 5 springs separated in their required relation, preserving the desired and established form of the resilient unit, while permitting it to function as a cushion in either reversed position. The air-tight covering of rubberized 10 cloth also assists in preserving the established form of the resilient unit and also permits it to function in either reversed position, while at the same time providing an inner air chamber, the effect of which is utilized in preserving 15 the desired cushioning effect.

The resilient unit constructed as described is entirely covered on the top, bottom and each of the four sides with a thick layer or 20 layers of padding 19, which may be of cotton or other suitable material, and is built up into the required shape, such as that shown in the drawing, and then provided with an outer covering or casing 21 of any desired material such as a suitable upholstery 25 fabric.

To utilize the air cushion, the rubberized cloth covering is provided with a vent opening 23 of such a size as to permit the slow escape of air from the resilient unit when 30 pressure is applied thereto. To better facilitate the functioning of the air cushion, such vent opening is connected to a flexible pipe or conduit, such as the short rubber tube 25, which extends through the intermediate wall 35 or padding to a vent opening 27 in the outer covering 21, the tube being joined to the fabric covering of the resilient unit and to the outer fabric by any suitable means, such as the flanged rubber union plates 29 and 31. 40 This connecting tube, which is adapted to yield under various movements of the cushion, provides for a more or less restricted admission of air to and escape from the inner air chamber of the cushion.

To control the escape and admission of air, the vent opening 27 may be covered by a plate 33 having a vent opening 35 which may be opened to varying degrees by the pivoted valve plate 37. If the padding 19 is sufficiently porous, a sufficient amount of air may be circulated directly from the padded portion of the cushion into and out of the inner air chamber, and to permit such circulation and minimize the amount expelled through 55 the outer vent opening and check any unnecessary noise which might accompany its expulsion or admission therethrough, one or more vent openings 39 may be formed in the walls of the vent tube.

Or, if desired, in place of employing the flexible pipe, the necessary expulsion of air from the inner chamber and admission of air thereto may be provided for, or in conjunction 60 with the use of the pipe may be assisted, by providing one or more ventilating open-

ings in the walls of the air chamber covering 13 and similar openings in the outer covering 21 of the cushion. In Fig. 1 of the drawings I have provided one such ventilating opening 70 in each side wall of the chamber covering 13 and in each side of the cushion covering 21 through the use in each case of a gauze-covered eyelet 41 fixedly held in a perforation of such side wall and of a size sufficient to give the required circulation of air. Such 75 ventilating devices in no wise impair the flexibility or the appearance of the cushion.

The finished cushion has the conventional appearance of a down stuffed cushion, being 80 plump, resilient and flexible through both its top and bottom. When pressure is applied to the cushion, as through the weight of a person seating himself upon it, the air is slowly expelled from the vent opening 23, escaping through the valve opening in the external covering 21 and in part into the padding through the opening in the wall of the flexible tube, the inner resilient unit of the cushion yielding gradually until the compression of the springs brings about a condition 85 of equilibrium. As soon as the weight is relieved, the springs expand, drawing air again into the air chamber of the resilient unit, again expanding the latter and expanding the entire cushion to its full, plump, original 90 form and shape.

The cushion is equally resilient on top and bottom, the internal resilient unit being elastic and compressible under pressure exerted from either top or bottom, and being covered 100 by padding on both top and bottom the resilient unit cushions and functions equally well and is equally well restored to its normal shape when relieved of pressure, whether the cushion is applied to a chair or sofa in 105 the position shown in the drawing, or in a reversed or up side down position.

While I have herein shown the principles of the invention as applied to a seat cushion for a chair or sofa, it may also be usefully 110 employed in other analogous cushion devices, such as mattresses, pillows or the like.

While I have herein shown and described for the purposes of illustration one particular embodiment of the invention, it is to be understood that extensive changes may be made in the form, relative arrangement of parts and materials used, all without departing from the spirit thereof.

I claim:

1. A pillow cushion having an internal resilient unit comprising a series of springs arranged side by side to give said unit as a whole a definite, characteristic but yieldable and more or less flexible form, a substantially air-tight, flexible covering enclosing said unit and providing an air chamber within the same, said chamber having a vent opening, an outer covering and padding surrounding said unit and providing a cushion 125

ioning resiliency at both the top and bottom of said resilient unit, a vent opening provided in the outer covering, and a flexible air pipe extending from said vent opening in the covering for said resilient unit to the vent opening in the outer covering.

2. A self-reshaping pillow cushion approximating in characteristics a down filled cushion and embodying an internal resilient unit comprising a series of readily yieldable helical springs arranged side by side to give said unit as a whole a definite and characteristic but readily yieldable and more or less flexible form, said readily yieldable unit constituting means for reshaping the cushion, a substantially air tight, flexible covering enclosing said unit and providing an air chamber within the same, said chamber having a vent opening, an outer covering and padding surrounding said unit and providing a cushioning resiliency at both the top and bottom of said resilient unit, said vented air chamber providing fluid pressure means to resist the sudden collapse of the unit by the seating of a person on the cushion and gradually diminish in resistance to relatively slowly transfer the collapsing pressure to the springs of said unit, whereby the characteristics of a down filled cushion are approximated while avoiding sudden complete collapse of said readily yieldable springs under such sudden application of pressure and providing for reshaping of the cushion when released.
3. A self-reshaping pillow cushion according to claim 2 including a restricted flexible air pipe extending from said vent opening and through the padding to the outer covering to establish direct but restricted communication between the interior of said unit and the atmosphere.

In testimony whereof, I have signed my name to this specification.

BENJAMIN OSTROFF.
